UNITED STATES PATENT OFFICE.

FRANK P. KOBERT, OF AMITYVILLE, NEW YORK.

ELECTRIC HEATING APPARATUS.

1,378,684.

Specification of Letters Patent. Patented May 17, 1921.

Application filed June 5, 1920. Serial No. 386,864.

To all whom it may concern:

Be it known that I, FRANK P. KOBERT, a citizen of the United States, and residing at Amityville, L. I., in the county of Suffolk and State of New York, have invented certain new and useful Improvements in Electric Heating Apparatus, of which the following is a specification, such as will enable those skilled in the art to which it appertains to make and use the same.

This invention relates to electric heating apparatus and particularly to apparatus of this class designed for use in connection with metal working machines, such as forging machines, electric riveting machines, welding machines and other apparatus of this class, and the object of the invention is to provide improved means for heating the metal or workpiece fed into a machine prior to the fashioning of said metal or workpiece into the desired form in order to facilitate the operation of forming such article and to produce a more perfectly formed product; a further object of the invention being to provide means whereby the heating element may be given a reciprocating movement, and whereby in one movement of said element the electrodes thereof will firmly grasp the metal or workpiece to be heated and advance the same into a machine or into position to be operated upon; a further object being to provide means for holding the metal or workpiece against movement in the other operation of said heating element; and a still further object being to provide means for controlling the circuit to the electrodes of the heating element whereby the circuit is closed and opened prior to the making and breaking of the contact of said electrodes with the metal or workpiece in order to prevent what are known as arcs or electric flashes between the electrodes and the metal or workpiece; and with these and other objects in view the invention consists in an electric heating apparatus of the class and for the purpose specified which is simple in construction and operation and efficient in use, and which is constructed and operated as hereinafter described and claimed.

The invention is fully disclosed in the following specification, of which the accompanying drawings form a part, in which the separate parts of my improvement are des-

ignated by suitable reference characters in each of the views, and in which:

Figure 1 is a diagrammatic view showing my improved heating element complete and the electrical apparatus coöperating therewith and the means for controlling the circuit to said apparatus;

Fig. 2 a partial section on the line 2—2 of Fig. 1 on an enlarged scale and showing a detail of the construction;

Fig. 3 a partial section on the line 3—3 of Fig. 1, and showing another detail of the construction;

Fig. 4 a partial section on the line 4—4 of Fig. 1 and on an enlarged scale;

Fig. 5 a partial section on the line 5—5 of Fig. 1, and on an enlarged scale; and,

Fig. 6 a partial section on the line 6—6 of Fig. 4.

In practice, I provide a suitable main frame 10 having bearings 11 and 12 in the lower end portion thereof, and in which is slidably mounted a shaft 13 adapted to be operated or given a forward and backward reciprocating movement by any suitable mechanism connected with the end portion 14 of said shaft.

The upper end portion of the main frame 10 is provided with other bearings 15 and 16 in which a shaft 17 is rotatably mounted. I also provide two supplemental frames 18 and 19 which are adapted to be adjustably connected with the shaft 13 and are movable with said shaft. The adjustment of the supplemental frames 18 and 19 on the shafts 13 is obtained through split bearings 20 at the lower end portions of said frames. The upper end portions of the supplemental frames 18 and 19 are yoke-shaped in form as shown at 21 and provided with bearings 22 and through which the shaft 17 passes, and keyed to the shaft 17 between the separate bearings 22 of said frames are cam devices 23 having cam grooves 24.

The supplemental frames 18 and 19 are provided approximately centrally thereof with elongated and vertically arranged apertures 25 in each of which is mounted a slide 26, and movably connected with the slides 26 of the supplemental frames 18 and 19 are electrodes 27 and 28 respectively, and other electrodes 29 and 30 are movably connected with enlarged portions 31 on the supplemental frames 18 and 19 below the slides 26.

The above described construction produces two pair of electrodes, one pair constituting the electrodes 27 and 29 and the other pair the electrodes 28 and 30. The movable connection of the electrodes 27 to 30 inclusive with the slides 26 and the enlarged portions 31 is to permit of a slight swivel action of said electrodes in their supports to insure perfect contact of said electrodes, or the 10 abutting arc-shaped faces 32 thereof on a workpiece 33 which, in the form of construction shown, consists of a rod or heavy wire.

The electrodes 27 and 28 are adapted to be moved vertically in the supplemental frames 18 and 19 respectively, and toward and from the workpiece 33 and, in the construction shown, said electrodes are operated through levers 34 rotatably mounted on 20 projecting studs 35 on the supplemental frames 18 and 19, one end of said levers being provided with anti-friction rollers 36 which are adapted to operate in the cam grooves 24 of the cams 23 and pivotally connected with the other ends of said levers 34 are links 37 which are also pivotally connected with the electrodes 27 and 28.

Mounted at one side of the supplemental frame 19 and between the separate parts of the bearing 16 and secured to the shaft 17 is a cam 38 having a cam groove 39 and a lever 40 is rotatably mounted on a support 41 which, in the construction shown, is formed integrally with the main frame 10 as shown in Fig. 5. One end of the lever 40 is provided with an anti-friction roller 42 which is adapted to operate in the cam groove 39 of the cam 38. A link device 43 is pivotally connected with the other end of said lever, and said link device carries a jaw member 44, which is pivoted thereto as shown at 45, and said jaw member is provided on its bottom face with an arc-shaped recess 46 which corresponds with a similar recess 47 formed in an extension 48 of the bearing 12. The extension 48 of the bearing 12 constitutes a stationary jaw member and the jaw member 44 is a movable jaw member which is moved toward and from the stationary jaw member through the operation of the lever 40 and link 43, and is adapted to grasp the workpiece 33 at intervals to hold the same against movement in one movement of the supplemental frames 18 and 19 and the electrodes carried thereby, as hereinafter described.

In Fig. 1 of the drawing I have indicated at 49 an electric transformer having the usual leads 50 and 51. The lead 50 is connected with the enlarged portion 31 with which the electrode 29 is connected, while the lead 51 is connected with the enlarged portion 31 with which the electrode 30 is connected. The electrodes 29 and 30 are 65 placed in electrical connection with the elec-

trodes 27 and 29 respectively through flexible conducting members 52 and 53, whereby the current from the transformer passes through leads 50—51 to the separate pairs of electrodes.

The electrodes 27 to 30 inclusive are provided with bores or passages 54 which extend transversely therethrough and water pipes 55 are connected with the sides of said electrodes to permit of the circulation of water through said electrodes for the purpose of cooling the same.

I also provide means for controlling the circuit to the transformer and thus to the electrodes whereby the current is turned on, after the electrodes have made contact with the workpiece and is shut off prior to the breaking of the contact of said electrodes with said workpiece. In accomplishing this result I provide a shaft 56 which is driven by any suitable means and properly timed with the rotation of the shaft 17 as well as the reciprocating movement of the shaft 13, contact disks 57 and 58 with which the main circuit wires 59 and 60 are connected through brushes 61. Other and segmental contact disks 62 and 63 are secured to the shaft 56 in juxtaposition to the disks 57 and 58, and the contact segments 64 of the disks 62 and 63 are placed in circuit with the contact faces 65 of the disks 57 and 58 through flexible conducting members 66. Brushes 67 are adapted to operate in connection with the disks 62 and 63 and are provided with wires 68 which connect with the transformer 49.

With the above-described construction it will be seen that a circuit from any suitable source will enter the transformer through member 44, which is pivoted thereto as shown at 45, and said jaw member is provided on its bottom face with an arc-shaped recess 46 which corresponds with a similar recess 47 formed in an extension 48 of the bearing 12. The extension 48 of the bearing 12 constitutes a stationary jaw member and the jaw member 44 is a movable jaw member which is moved toward and from the stationary jaw member through the operation of the lever 40 and link 43, and is adapted to grasp the workpiece 33 at intervals to hold the same against movement in one movement of the supplemental frames 18 and 19 and the electrodes carried thereby, as hereinafter described.

It will be understood that the supplemental frames 18 and 19 may be adjusted longitudinally of the shaft 13 to govern the length of the workpiece 33 to be heated, or that portion of the workpiece which it is desired to heat, and in the operation of the machine and with the workpiece in position between the electrodes and the jaw members 44 and 48, the rotation of the shafts 17 and 56 will rotate the cams 23 and 38 as well as the contact disks 57 and 58, 62 and 63, and the jaw member 44 will be moved out of engagement with the workpiece 33 and the electrodes 27 and 28 moved downwardly to grasp the workpiece 33, after which the circuit from the transformer to said electrodes will be completed through the contact disks 62 and 63.

63 and the shaft 13 will then be moved in the direction of the arrow α Fig. 1 by any suitable means, in which operation the supplemental frames 18 and 19 with the various parts connected therewith will be advanced 5 in said direction on the shaft 17 and the workpiece 33 will be fed into the machine in this operation and heated, while it is fed into the machine by reason of the firm contact of the electrodes therewith. After the supplemental frames 18 and 19 have reached the limit of their movement in the direction of the arrows α , the circuit through the transformer to the electrodes is broken 10 through the contact disks 62 and 63, after which the electrodes 27 and 28 are moved upwardly and the jaw member 44 is moved into position to grasp the workpiece 33 to hold the same in position, and the shaft 13 is 15 then moved backwardly into its normal position in which operation the supplemental frames 18 and 19 and the various parts connected therewith are moved backwardly over the shaft 17 and the workpiece 33, and when 20 the supplemental frames have reached the limit of their backward movement the electrodes 27 and 28 are again moved into operative position and the jaw member 44 moved into inoperative position, and the above operation 25 again repeated.

From the foregoing it will be apparent that my improved heating apparatus may heat a workpiece of predetermined dimensions and feed the same into a suitable upsetting or riveting machine, while the same is being heated I may intermittently feed a workpiece of indefinite length into a machine and intermittently heat the same in such operation, and while I have shown certain details of construction for carrying my invention into effect, it will be apparent that I am not necessarily limited to these details nor to the feeding and heating of a workpiece of any specific form or dimensions, and 45 various changes in and modifications of the details of construction herein shown and described may be made, within the scope of the appended claims without departing from the spirit of my invention or sacrificing its 50 advantages.

With my improved heating apparatus I may heat workpieces of predetermined dimensions prior to the fashioning of said workpieces, or I may heat a strip or sheet of material indefinitely throughout its entire 55 length in the operation of passing it into the machine and through electrodes, and it will also be apparent that I may also heat predetermined portions of a workpiece of given 60 dimensions, such for example, one end portion of a rod or bar which end portion is to be headed or fashioned in any desired manner, or a workpiece of indefinite length such as a rod or wire may be heated at predetermined points throughout its length, and the 65

heated portions fashioned into the desired form. It will be understood that in the last named operation separate workpieces will be cut from the stock in the usual manner.

Having fully described my invention, 70 what I claim as new and desire to secure by Letters Patent, is:—

1. A heating apparatus comprising two movable electrodes, said electrodes being spaced longitudinally of and adapted to engage a workpiece to feed it into a suitable machine, and means whereby said workpiece will be heated in the operation of feeding the same into a machine by said electrodes. 75

2. A heating apparatus comprising two spaced electrodes, said electrodes being adapted to engage a workpiece to feed it into a suitable machine, means whereby said workpiece will be heated in the operation of feeding the same into a machine, and means for controlling the circuit to said electrodes to close the circuit after the electrodes are brought into firm contact with said workpiece and to open the circuit prior to the breaking of the contact of said electrodes with said workpiece. 80

3. A heating apparatus of the class described comprising two electrodes, means for adjusting said electrodes toward and from each other on a suitable support, said electrodes being adapted to receive a workpiece, means for firmly grasping said workpiece in said electrodes, and means for giving said electrodes a reciprocating movement to feed the workpiece supported therein into a suitable machine. 95

4. A heating apparatus of the class described adapted to heat predetermined portions of a workpiece of indefinite length and to feed said workpiece into a suitable machine in the operation of heating the same, comprising two electrodes spaced longitudinally of said workpiece, means whereby said electrodes may be operated to firmly grasp said workpiece in the operation of feeding said workpiece into the machine, and means for controlling the circuit to said electrodes whereby the circuit is completed after the electrodes are in firm contact with the workpiece. 100

5. A heating apparatus of the class described adapted to heat predetermined portions of a workpiece of indefinite length and to feed said workpiece into a suitable machine in the operation of heating the same, comprising two electrodes spaced longitudinally of said workpiece, means whereby said electrodes may be operated to firmly grasp said workpiece in the operation of feeding said workpiece into the machine, and means for controlling the circuit to said electrodes whereby the circuit is completed after the electrodes are in firm contact with the workpiece and whereby the circuit to said electrodes is broken prior to 110

the disengagement of said electrodes from a class described comprising a suitable frame, said workpiece, and the like, and a shaft mounted in said frame and adapted to

6. A heating apparatus of the class described to be given a forward and backward reciprocating motion.

10 electrodes being composed of separate parts, a workpiece mounted between said electrodes, one of which is movable toward and from the other to firmly grasp the workpiece, means for operating the movable electrodes and the separate pairs thereof, means for operating the movable electrodes in each pair of the electrodes to firmly grasp a pair, and means for closing the circuit to workpiece between the separate parts of said electrodes after the separate pairs

15 said electrodes, and means for adjustably thereon have been moved into firm contact 80) mounting said electrodes on a reciprocating with the workpiece, and a vertical support 85) support. 11. An electric heating apparatus of the

7. A heating apparatus of the class described comprising a suitable frame, a shaft mounted in said frame and adapted

20 tions of a workpiece of indefinite length to be given a forward and backward recip- 85 and to feed said workpiece into a suitable rotating movement therein, supplemental machine in the operation of heating the frames adjustably connected with said shafts.

25 same, comprising two electrodes spaced longitudinally of said workpiece, each of said electrodes being composed of separate parts, a pair of electrodes mounted in connection with each of said supplemental frames, one electrode being movable toward and from the other, means for operating the movable electrodes, and a workpiece mounted between said electrodes, one of which is movable toward and from the other to firmly grasp the other, means for operating the movable electrodes, and a workpiece mounted between said electrodes.

30 the said means for operating the movable workpiece mounted between said electrodes parts of the electrodes to firmly grasp a hand and then separate pairs thereof, means workpiece between the separate parts of whereby in one movement of said reciprocating shaft the movable electrodes in each 95 said electrodes, means for adjustably mounting said electrodes on a reciprocating support will be held in firm contact with the workpiece, and a swivel support for said electrodes to feed the same into a suitable

8. A heating apparatus of the class described, comprising a heating coil, a workpiece to feed the same into a suitable machine, and means for closing the circuit to said electrodes when in firm contact with

35 scribed adapted to heat predetermined portions of a workpiece of indefinite length and to feed said workpiece into a suitable machine in the operation of heating the 12. An electric heating apparatus of the

same, comprising two electrodes spaced longitudinally of said workpiece, each of said electrodes being composed of separate parts 40 class described comprising a suitable frame, a shaft mounted in said frame and adapted 105 to be given a forward and backward recip-

45 one of which is movable toward and from the other, means for operating the movable parts of the electrodes to firmly grasp a workpiece between the separate parts of said electrodes, means for adjustably mounting 110 the electrodes in the respective frames, and a shaft to be given a forward and backward reciprocating movement therein, supplemental frames adjustably connected with said shaft, a pair of electrodes mounted in connection with each of said supplemental frames, one of the electrodes in each pair being movable

50 said electrodes, means for adjustably mounting said electrodes on a reciprocating support, a swivel support for said electrodes, and means for cooling the separate parts of said electrodes.

9. An electric heating apparatus of the

- class described comprising a suitable frame, a shaft mounted in said frame and adapted to be given a forward and backward reciprocating movement therein, supplemental frames adjustably connected with said shaft, a pair of electrodes mounted in connection with each of said supplemental frames, one of the electrodes in each pair being movable toward and from the other to firmly grasp 5 a workpiece mounted between said electrodes and the separate pairs thereof, means whereby in one movement of said reciprocating shaft the movable electrodes in each pair will be held in firm contact with the 10 workpiece to feed the same into a suitable machine, means for closing the circuit to said electrodes when in firm contact with said workpiece to heat the same in the operation of feeding the workpiece into a machine, and whereby in the other movement 15 of said shaft the separate pairs of electrodes will be moved out of engagement with said workpiece, means for breaking the circuit to said electrodes prior to the disengagement of said electrodes from said workpiece, and means for holding the workpiece against movement in the last named operation 20 of said reciprocating shaft and said electrodes. 25 14. An electric heating apparatus of the class described comprising a suitable frame, a shaft mounted in said frame and adapted to be given a forward and backward reciprocating movement therein, supplemental frames adjustably connected with said shaft, a pair of electrodes mounted in connection with each of said supplemental frames, one of the electrodes in each pair being movable toward and from the other to firmly 30 grasp a workpiece mounted between said electrodes and the separate pairs thereof, means whereby in one movement of said reciprocating shaft the movable electrodes in each pair will be held in firm contact with the workpiece to feed the same into a suitable machine, means for closing the circuit to said electrodes when in firm contact with said workpiece to heat the same in the operation of feeding the workpiece into a machine, and whereby in the other movement 35 of said shaft the separate pairs of electrodes will be moved out of engagement with said workpiece, means for breaking the circuit to said electrodes prior to the disengagement of said electrodes from said workpiece, and means for holding the workpiece against movement in the last named operation 40 of said reciprocating shaft and said electrodes. 15. A heating apparatus comprising two pairs of movable electrodes, the separate pair of electrodes being spaced longitudinally of and adapted to engage a workpiece to feed it into a suitable machine, and means whereby that portion of the workpiece between the separate pairs of electrodes will be heated in the operation of feeding the same into a machine by said electrodes. 16. A heating apparatus of the class described adapted to heat predetermined portions of a workpiece of indefinite length and to feed said workpiece into a suitable machine in the operation of heating the same, comprising movable electrodes spaced longitudinally of said workpiece. 70 75

In testimony that I claim the foregoing as my invention I have signed my name this 3rd day of June, 1920.

FRANK P. KOBERT.
